UNITED STATES PATENT OFFICE.

WINFIELD L. KING, OF INDIANA, PENNSYLVANIA.

RAZOR-GUARD.

1,081,123.

Specification of Letters Patent.

Patented Dec. 9, 1913.

Application filed March 25, 1913. Serial No. 756,677.

To all whom it may concern:

Be it known that I, WINFIELD L. KING, a citizen of the United States, and a resident of Indiana, in the county of Indiana and 5 State of Pennsylvania, have invented a new and Improved Razor-Guard, of which the following is a full, clear, and exact description.

My invention relates to a guard attachment for the blades of ordinary razors, and 10 particularly to an attachment comprising a clamp and a swinging guard.

It is a design of my invention to provide a guard attachment of the indicated character 15 that will effectively guard the cutting edge of the razor against accidentally cutting the face of the user, and to so arrange the clamp element and the guard, that the latter will exert a pressure against the 20 clamp to bind the same against the razor blade.

The invention will be particularly explained in the specific description following.

Reference is to be had to the accompanying drawings forming a part of this specification, in which similar characters of reference indicate corresponding parts in all 25 the views.

Figure 1 is a side elevation of my improved attachment, showing the same applied to a razor blade; Fig. 2 is a similar view of the opposite side; and Fig. 3 is a cross section on an enlarged scale.

In forming an attachment in accordance 30 with my invention, a clamp is produced, consisting of jaws 10 and 11, there being preferably two jaws 10 lying at one side of the blade, and a single elongated jaw 11 at the opposite side and joined to the jaws 10 35 by U-bends 12 at the ends, that arch over the back of the razor blade A, when the device is applied.

The elongated jaw 11 has ears 13 near the ends, in which is pivoted the swinging guard 40 45 14, provided with teeth 14' adapted to be disposed with their ends adjacent to the cutting edge of the razor blade A. It is to be noted that the guard 14 is pivoted directly to the jaw 11, and not to a separate carrying member for the guard. The guard adjacent to the pivoted edge is bent at an angle, or flanged as at 14", and the said flange is

adapted to exert pressure on the jaw 11, for which purpose the said jaw is formed with studs 15, which may be located at such points 55 on the jaw as will result in an effective pressure being exerted on the jaw by the bent flange 14", when the guard is turned on its pivot to a position against the razor blade, the edge of the flange riding onto the said 60 sides and exerting a pressure thereon as the guard swings past its center.

The pressure of the flange 14" presses the jaw 11 inwardly against the adjacent side of the clamp of the guard to retain the guard against the razor blade; therefore the closing down 65 of the clamp of the guard to retain the guard against the razor blade, will result in increasing the clamping action of the jaws on the blade. On the other hand, when the guard is swung upward away from the 70 blade, for instance to the position indicated by dotted lines in Fig. 2, the flange 14" will be disengaged from the jaw 11 and pass out of contact with the studs or protuberances 15, relieving the said jaw of pressure so that 75 it will hold with less binding contact onto the razor blade.

The comparative loosening of the jaws in their grip on the blade results in less scratching or marring of the sides of the blade by 80 the jaws when the attachment is removed or applied.

Having thus described my invention, I claim as new and desire to secure by Letters Patent:

1. A guard attachment for razor blades, comprising a clamp presenting a pair of jaws adapted to embrace the opposite side faces of the razor blade, one of said jaws being laterally flexible to be flexed toward 90 the opposite jaw for contracting the space between the jaws, and a guard pivoted to the clamp for swinging movement and having a member disposed adjacent to the flexible jaw, and movable upon the swinging of 95 the guard into engagement with the flexible jaw to flex the same in the direction of the companion jaw of the pair.

2. A guard attachment for razors, comprising a clamp presenting at one side an 100 elongated jaw and at the opposite side spaced jaws united to the elongated jaw near the ends of the latter by U-bends, and a swinging guard pivoted to the elongated

jaw between the top and bottom of the latter, the said guard having a flange at an angle thereto, and the elongated jaw having protuberances against which said flange has 5 frictional engagement to flex the jaw laterally and for pressing the same against the side of the razor blade.

In testimony whereof I have signed my name to this specification in the presence of two subscribing witnesses.

WINFIELD L. KING.
